UNITED STATES PATENT OFFICE

GASTON JULES DEMOUCRON, OF PARIS, FRANCE

BOOT LAST

Application filed February 24, 1928, Serial No. 256,751, and in France February 24, 1927.

The present invention relates to boot-lasts and the main object of the said invention is to ensure that the tensions on the two flanks of boots and shoes are the same.

Another object of the invention is that the boot-last can indifferently be used for a right shoe or a left shoe or boot.

A further object of the invention is to provide a simple boot-last which can be taken to pieces so as to easily ensure the replacement of the various parts in case of breakage of one of them.

Forms of construction of improved boot-lasts in accordance with the invention are illustrated by way of example only, in the accompanying drawing in which:

Fig. 1 is an elevation and longitudinal section of a first form of construction.

Fig. 2 is a corresponding plan view.

Fig. 3 is a plan view and partial section of a second form of construction.

Fig. 4 is an underside partial plan view of a third form of construction.

Fig. 5 is an underside partial plan view of a fourth form of construction.

The boot-lasts described and illustrated each comprise a resilient blade 1, one of the ends of which is provided with a member 2 taking a bearing on the rear stiffener of the boot or shoe, and the other end of which is secured on a member 3 constituting a connection between the resilient blade 1 and two movable parts 4 arranged on either side of the member 3 and used for uniformly pressing the inner flanks of a boot or shoe. The movable members 4 are connected at their front part by any suitable means allowing a relative displacement, on the one hand of these members 4 relatively to each other and, on the other hand, of the whole structure constituted by these two members relatively to the member 3.

In the example illustrated in Fig. 1 the device for connecting the members 4 is composed of a tube 5, slightly curved and freely sliding in a perforation 6 provided in the member 3. The ends of the tube 5 respectively fit into perforations 7 formed in the members 4. The tube 5, after assemblage, 50 is flared at its ends for maintaining the mem-

bers 4 in a position corresponding to the maximum spacing apart of these latter.

A spring 8 fits in recesses 9 provided in the members 4 and its ends bear on the bottoms of the said recesses. The spring 8 is guided by the member 3 and, for that purpose, it freely passes through a perforation 10 formed in the latter. The front connection of the members 4 which is realized by the tube 5 can be very simply obtained by a screw secured in one of the movable members 4 freely playing in the perforation 6.

It will be seen that the end of the boot-last, after its introduction in the boot or shoe, suitably orientates relatively to the latter, and independently of the mounting, by sliding of the spring 8 in the opening 10 of the member 3. The flanks of the boot or shoe then directly react on each other through the medium of the members 4 and of the spring 8. The uniform distribution of the tensions on the flanks of the boot or shoe is obtained either with a standard boot-last indifferently used for the left shoe or the right shoe or boot, or by means of special boot-lasts adopted for certain boots or shoes and which comprise a right boot-last and a left boot-last.

In the example illustrated in Fig. 3, the connection between the members 4 is ensured, at the front part of the latter, by a small plate 10 which is rigidly secured to the member 3 through the medium of rivets 11 for instance. The member 10 is provided with suitably arranged ports 12 in which can move rivets or screws 13 rigid with the members 4. The small plate 10 is arranged either under the members 3 and 4, or in ports provided in the said members. In this form of construction, the resilient device interposed between the members 4, is constituted by a resilient blade 14 which freely moves, on the one hand, in a port 15 formed in the member 3 and, on the other hand, in grooves 16 provided in the sides of the members 4.

In the example illustrated Fig. 4, the front connecting member of the members 4 is constituted by a small V-shaped plate 17 capable of pivoting on the member 3 about an axis 18. Screws 20, rigid with the members 3, 100

pass through ports 19, provided at the ends of the small plate 17.

In the example illustrated in Fig. 5, the front connecting element of the members 4 is constituted by a small plate 21 centrally provided with a port 22 permitting the displacement of this plate 21 relatively to the member 3. The members 4 are pivoted, in this case, about axes 23, as illustrated in Fig. 10. 5. The resilient members interposed between the members 4 are constituted, in this form of construction, by resilient blades 24, secured on the member 3, at 25, and taking a bearing, on the parts 4, by engagement of their free ends in grooves 26 provided in the inner sides of the members 4.

The boot-lasts described by way of example only can be easily taken to pieces and the various parts constituting them can be replaced 20 in case of breakage of one of them.

What I claim as my invention and desire to secure by Letters Patent is:

1. In a boot-last comprising a part for connecting a heel-piece with a toe piece, a central member perforated at the front part, flank members perforated at their front part, a connecting member freely fitted in the perforations of the central member and of the flank members, and resilient members for spacing apart the two flank members.

2. In a boot-last comprising a part for connecting a heel-piece with a toe piece, a central member perforated at the front part, and in its middle or rear portion, flank members 35 perforated at their front part, a tube flared at its ends and freely fitted into the front perforation of the central member and the front perforations of the flank members, and a resilient member interposed between the 40 flank members and freely passing through the middle or rear perforation of the central member.

In testimony whereof I have signed my name to this specification.

45 GASTON JULES DEMOUCRON.
